DUAL CARBURETOR

Charles L. Martin, Overland, Mo., assignor to
 Carter Carburetor Corporation, St. Louis, Mo.,
 a corporation of Delaware

Application September 4, 1943, Serial No. 501,331

11 Claims. (Cl. 123—127)

1

This invention relates to internal combustion engines and consists particularly in novel means for controlling the supply of combustible mixture thereto.

There have been suggestions for providing a multi-cylinder internal combustion engine, particularly of the automotive type, with dual fuel intake conduits having throttle valves capable of independent of selective action for separately controlling groups of cylinders. This is of particular advantage in an automotive engine in which considerable economy can be attained by operating less than all the cylinders when only a portion of the power capacity of the engine is being utilized. However, when one throttle valve is closed to cut off a group of cylinders, a suction drag is created in these cylinders, the over-coming of which uses a part of the power output of the operating cylinders. The waste of power and fuel has been overcome by providing an extra suction breaking valve which admits air to the non-firing or auxiliary cylinders, or by fully opening the throttle valve on the non-firing side. The latter means requires, of course, a device other than the throttle valve for cutting off the fuel supply.

An object of the present invention is to provide simplified means for controlling the supply of fuel to one of the mixture conduits or to a portion of the cylinders while permitting the flow of air to the auxiliary cylinders at all times so that a suction drag is not set up when some of the cylinders are cut out.

A further object is to provide a novel device of the above character including means causing substantial initial opening of the fuel control valve to insure the prompt formation of a combustible mixture with the air flowing through the mixture conduit.

Another object is to provide an auxiliary fuel control device, operated by the throttle controlling the constantly running cylinders, with means permitting partial independent closing of the main throttle valve, after the auxiliary fuel valve is opened, and partial independent opening of the main throttle as the auxiliary valve is closed, whereby the sudden change in power, as the auxiliary cylinders start to operate and cut out, may be damped.

These objects and other more detailed objects hereafter appearing are attained by the structure illustrated in the accompanying drawings in which:

Fig. 1 is a diagrammatic top view representing an eight cylinder internal combustion engine of

2

the automotive type with fuel supply manifolds and a carburetor embodying the present invention.

Fig. 2 is a side view of a carburetor and controls, partly sectioned, showing the parts in the positions assumed with the engine idling, certain parts in broken lines being shown in the positions they assume when the engine is at rest.

Fig. 3 is a vertical transverse section through the carburetor, the parts being in the same positions as in Fig. 2.

Fig. 4 is a view similar to Fig. 2, but showing the auxiliary fuel valve about to be tripped during opening movement of the main throttle.

Fig. 5 is a view similar to Fig. 3, but showing the auxiliary fuel valve just after tripping by continued main throttle opening.

Fig. 6 is a similar view showing the main throttle and auxiliary fuel valve held wide open for full speed operation. And

Fig. 7 is a view similar to Fig. 4, but showing the auxiliary fuel valve tripped as the result of lowering of the suction resulting from increased power demands upon the engine.

Fig. 8 is a detail inside view of the auxiliary valve snap.

The engine represented in Fig. 1 comprises a block 10 having cylinders designated 1 to 8, inclusive, each having an intake and an exhaust port with suitable valves (not shown). A pair of separate intake manifolds 11 and 12 connect, respectively, the intake ports of cylinders 1, 2, 7 and 8 and 3, 4, 5 and 6 with the outer or main and inner, or auxiliary barrels of the carburetor, generally indicated at 13. The usual exhaust manifold, connecting the exhaust ports of the cylinders to the exhaust pipe, is omitted.

The carburetor, shown in greater detail in Fig. 3, is of the downdraft, double barreled type including a common air inlet horn 14, a main mixture conduit 15 having multiple venturis 16 and a butterfly throttle valve 17, and an auxiliary mixture conduit 18 having multiple venturis 19, but having no control at its outlet portion, corresponding with main throttle 17. A central partition, including parts 20 and 21 extends the length of the carburetor between the mixture conduit, choker valve 22 being cut as at 23 to accommodate upper partition 21. The choker valve may be controlled by any suitable manual or automatic control attached to shaft 24.

Adjacent the mixture conduits is a fuel bowl 27 within which fuel is maintained at a substantially constant level by the usual float and needle valve mechanism (only the float being shown) and pro-

vided with a main metering orifice 28 in the lower portion thereof. Orifice 28 is controlled by a metering pin 29 carried at its upper extremity by a centrally pivoted lever 30 connected at its other end, by a link 31, to an arm 32 rigid with throttle shaft 33. A main fuel passage supply 34 extends upwardly at an angle from metering orifice 28 and terminates in main nozzle 35 discharging into the smallest or innermost venturi 16. An interconnected idling system includes passages 36, 37 and 38 connecting the main nozzle passage with idling ports 39 and 40 located adjacent the edge of throttle valve 17 when closed.

A second metering orifice 45 located in the fuel bowl communicates with an upwardly inclined auxiliary fuel passage 46 which terminates in a nozzle 47 discharging into the smallest or innermost venturi 19 in auxiliary mixture conduit 18. Orifice 45 is controlled by a metering pin 48 operated by a centrally pivoted lever 49 connected at its inner end by a link 50 to throttle arm 32. Both the metering pin operating linkages are arranged to lift the supported pins as throttle 17 is opened, to increase the effective openings in the metering orifices and enrich the mixture supplied by the nozzles. The calibration of main metering pin 29 does not necessarily conform with that of auxiliary pin 48.

Pivottally mounted within the smallest venturi 19, on a shaft 51, is a small butterfly-type valve 52 which controls the discharge from auxiliary fuel nozzle 47. The operating mechanism for this valve is better shown in Figs. 2, 4, 5, 6, 7 and 8. Rigid with valve shaft 51 outside the barrel is a lever having opposite arms 55 and 56. A second lever 57 is pivoted to the upper extremity of arm 56, on pin 58, and has a central transverse slot 59 receiving the extremity of valve shaft 51. The lower portion of lever 57 has inwardly extending ears 60 and 61 at opposite sides thereof, and is connected by a pin 62 to links 63 and 64. Link 64 has a longitudinal slot 65 at its opposite extremity receiving a pin 66 carried by an arm 67 rigid with main throttle shaft 33. A second arm 68 on the same end of the throttle shaft has an aperture 69 in its extremity for connection to suitable accelerator linkage extending in the usual manner to the driver's compartment. Arm 68 has a lug 70 carrying a throttle adjusting screw 70^a for engaging a fixed stop 71 on the carburetor barrel.

A cylinder 75 mounted on a bracket 76 adjacent the carburetor barrel slidably receives a piston 77 constantly urged to the left by a coiled spring 78. A threaded cap 79 on the end of the cylinder provides for adjusting the spring. The cap has a tapped hole 80 for attachment of a tube 81 connecting the cylinder to main intake manifold 11. A rod 82 extends leftwardly from the piston through a loosely fitting hole 83 in the left hand end of the cylinder and has a pin 84 received in a slot 85 in the right hand end of previously mentioned link 63.

Overlapping levers 56 and 57 constitute a snap action device, the over-center action being enforced by a tension spring 86 stretched between pin 58 and a pin 87 rigid with the carburetor body.

This mechanism operates as follows:

The rest position of piston 77 and main throttle 17 is represented by the broken line positions of these parts in Fig. 2. To start the engine, throttle 17 is moved to a somewhat more open position, the lost motion in slot 65 permitting this without affecting the remainder of the linkage.

When the engine starts to run and the throttle is closed, piston 77 will be drawn to the right by the manifold suction, as in solid line in Fig. 2. Then, as the throttle valve is opened for acceleration, as to the position in Fig. 4, link 64 will be moved leftwardly, swinging lever 57 clockwise until right hand ear 61 thereon engages lever arm 55 rigid with valve shaft 51. Upon slight continued throttle opening movement, lever 55, 10 56 will pass over-center, whereupon spring 86 will cause it to snap to the position in Fig. 5, in which shaft 51 is at the left hand side of slot 59 and valve lever 55 is rotated clockwise so as to substantially open small valve 52. Thereafter, valves 15 52 and 17 move outward together.

The distance between ears 60 and 61, and slot 65 provide for limited movement of small valve 52 under the influence of varying suction, as applied to piston 77, when main throttle 17 is in 20 intermediate position. Fig. 7 is similar to Fig. 4 except that small valve 52 has been tripped by suction, main throttle 17 remaining in a fixed position. Thus, it is possible for the auxiliary mixture conduit to cut in and cut out by snap 25 action in accordance with load requirements.

In Fig. 6, the main throttle 17 and auxiliary fuel valve 52 are both held in wide open position for full speed operation. During the first part of the closing of throttle 17, pin 66 on the throttle 30 arm 67 is shifted to the lower end of slot 65 and ears 60 on snap action lever 57 are moved against valve operating lever 55 before any movement of valve 52 occurs. Valve 52 and the throttle close together until the valve reaches the position of 35 Fig. 5 and then snaps shut, as in Fig. 4.

Thus, the single valve 52 controls the emission of fuel from auxiliary nozzle 46 and provides for constant passage of air to inner or auxiliary cylinders 3, 4, 5 and 6 regardless of whether they 40 are firing or not. The snap action of this valve prevents the supplying of fuel at an insufficient rate to form a proper firing charge with the air passing around and through the venturis. Slot 65 in link 64 permits partial closing of main throttle 17, when the auxiliary cylinders start to operate and also partial opening of the throttle as the auxiliary cylinders cut out so as to reduce the resultant sharp change of power. The ultimate effect of this is to permit the operator to 50 to obtain a smooth variation in torque during transfer from four to eight cylinder operation as would occur when the auxiliary cylinders start to operate since no idling system is provided for low speed operation of these cylinders.

The invention may be modified in various respects as will occur to those skilled in the art and the exclusive use of all modifications as come within the scope of the appended claims is contemplated.

I claim:

1. In an internal combustion engine, main and auxiliary fuel mixture conduits individually feeding the engine, a throttle valve controlling the mixture discharged from said main conduit, a restricted tube mounted in said auxiliary conduit and spaced from the walls thereof, a main fuel nozzle discharging into said main conduit, an auxiliary fuel nozzle discharging into said restricted tube, a valve controlling the passage through said tube, and means to operate said valve to control the discharge from said auxiliary fuel nozzle without affecting the air which passes around said restricted tube.

2. In an internal combustion engine, separate 70 main and auxiliary fuel mixture intake conduits

ndividually feeding the engine, a main fuel nozzle discharging into said main conduit, a throttle controlling the mixture discharged from said main conduit, a Venturi tube mounted in said auxiliary conduit and spaced from the walls thereof, an auxiliary fuel nozzle discharging into said tube, and a butterfly valve pivoted in said tube and controlling the passage of air through said tube and the discharge of fuel from said auxiliary nozzle.

3. In an internal combustion engine, separate main and auxiliary fuel mixture intake conduits individually feeding the engine, a throttle valve in said main conduit and a fuel nozzle discharging thereinto, multiple Venturi tubes in said auxiliary conduit, an auxiliary fuel nozzle discharging into the smallest of said tubes, and a butterfly throttle pivoted in said last-mentioned tube and controlling the passage of air through said tube and the discharge of fuel from said auxiliary nozzle, the space around said smallest Venturi tube providing for constant feeding of air to the engine regardless of the emission of fuel from said auxiliary nozzle.

4. An internal combustion engine as specified in claim 3 in which each of said mixture conduits supplies a separate cylinder or group of cylinders.

5. In an internal combustion engine, separate main and auxiliary mixture conduits each supplying a separate cylinder or group of cylinders, a main fuel nozzle and a manual throttle for one of said conduits, multiple Venturi tubes in the other conduit, an auxiliary fuel nozzle, discharging into the inner one of said tubes, a valve mounted on said inner tube and controlling the passage of air therethrough and thereby, the emission of fuel from said auxiliary nozzle, and operating means for said valve including a snap action device for causing substantial initial opening of said valve to insure prompt formation of a combustible mixture with the air passing through and around said inner Venturi tube.

6. In an internal combustion engine, a pair of mixture conduits each supplying a separate cylinder or group of cylinders, a fuel nozzle and a manual throttle for one of said conduits, multiple Venturi tubes in the other conduit, an auxiliary fuel nozzle discharging into the inner one of said tubes, a valve mounted on and controlling the passage of air through said inner tube and, thereby, the emission of fuel from said auxiliary nozzle, and means connecting said manual throttle and said valve for operating said valve responsive to movements of said throttle, said means including a snap action device for causing substantial initial opening and rapid final closing of said valve to insure formation of a combustible mixture with the fuel discharged from said auxiliary nozzle, and said means also including a lost motion element whereby opening movement of said throttle may be continued after said snap action of said valve.

7. In an internal combustion engine, a pair of fuel mixture conduits individually feeding the engine, a main fuel nozzle and a manual throttle for one of said conduits, multiple Venturi tubes in the other conduit, an auxiliary fuel nozzle discharging into the inner one of said tubes, a valve

mounted in and controlling the passage of air through said inner tube and, thereby, the emission of fuel from said auxiliary nozzle, and valve operating means comprising a lost motion connection between said throttle and said valve for operating said valve responsive to movements of said throttle.

8. An internal combustion engine as described in claim 7 in which said valve operating means further includes means responsive to engine suction for operating said valve within the limits of said lost motion connection.

9. An internal combustion engine as described in claim 7 in which said valve operating means further includes a snap action device incorporated with said lost motion connection for causing substantial initial opening and rapid final closing of said valve to insure formation of a combustible mixture with air passing through and around said inner Venturi tube whenever said auxiliary nozzle is discharging.

10. An internal combustion engine as described in claim 7 in which said valve operating means further includes an engine suction responsive device for operating said valve within the limits of said lost-motion connection, and a snap-action device, for causing substantial initial opening and rapid final closing of said valve to insure formation of a combustible mixture with air passing through and around said inner Venturi tube whenever said auxiliary nozzle is discharging.

11. In an internal combustion engine, a fuel mixture supply conduit, multiple Venturi tubes arranged serially in said conduit, a fuel nozzle discharging into the inner one of said tubes, said conduit outside said last-mentioned Venturi tube being constantly open for supplying air to the engine, a valve mounted on and completely controlling said inner Venturi tube to control the discharge of fuel from said nozzle, and manual means to operate said valve including a snap action device for insuring fully closed or substantially open positioning of said valve so that sufficient fuel is discharged by said nozzle to form a combustible mixture with the air entering through and around said inner Venturi tube at all times that said nozzle is discharging.
